UNITED STATES PATENT OFFICE.

CHRISTOPHER P. JÜRGENSEN, OF COPENHAGEN, DENMARK.

ELECTRIC-ARC LAMP.

SPECIFICATION forming part of Letters Patent No. 270,954, dated January 23, 1883.

Application filed September 27, 1882. (No model.)

To all whom it may concern:

Be it known that I, CHRISTOPHER PETER JÜRGENSEN, professor, of Copenhagen, in the Kingdom of Denmark, have invented certain new and useful Improvements in Electric Lamps, of which the following is a specification.

This invention has reference to an improved construction of electric-arc lamps having two movable carbon-holders which are operated by frictional contact with two grooved circular disks or pulleys placed on a common axis and by the action of two solenoids which inclose the two soft-iron extensions of the carbon-holders, the size of the arc between the carbon points being regulated by the solenoids and by a contact apparatus that is electrically connected therewith and with the source of electricity. One of the solenoids is wound with two coils, an inner of finer and an outer of coarser wire, as will appear more fully hereinafter.

In the accompanying drawings, Figure 1 represents a side elevation of my improved electric lamp. Figs. 2 and 3 are details of the same, and Fig. 4 is a diagram illustrating the relative position of the solenoids and carbon-holders and their connection with the contact apparatus and source of electricity.

Similar letters of reference indicate corresponding parts.

In the drawings, K K' represent the carbon-holders, which are respectively supported by frictional contact with two circumferentially-grooved disks or pulleys, h and H, that are fixed on a common shaft, x, supported in suitable bearings of the transverse strips e of the lamp-casing. The turning of the pulleys h H around their axis x in one direction causes the raising of one carbon-holder and the simultaneous lowering of the other carbon-holder, while the turning of the pulleys in opposite direction causes the lowering of the first carbon-holder and the raising of the second carbon-holder. Both carbon-holders K K' are guided by suitable bushes or sleeves in the top plate, C', of the lamp-casing C, the carbon-holder K being insulated from the top plate, C', of the casing. Both carbon-holders K K' are provided with extension-rods of soft iron that extend into the hollow cylindrical space of the

solenoids S and S', respectively. The radii of the actuating-disks H and h are made in the proportion of two to one, so as to provide for the quicker burning off of the positive carbon pole during the same period of time. As both carbons are fed forward simultaneously by the disks and in proportion to their burning, the arc is maintained at the same point.

The contact apparatus R is insulated from the lamp-casing and composed of an electromagnet, m, an armature, a, that is pivoted to a standard, v, and held by a tension-spring in contact with an adjustable screw, b, of a standard, o. The tension-spring of the armature a is applied to a standard, y, as shown clearly in Fig. 3.

The solenoid S is formed of two coils, of which the inner, t', is of finer wire and wound in opposite direction to the outer coil, t. The inner coil, t', is connected to the binding-post p and to the outer coil, t, while the latter is connected with the binding-post p' and with the supporting-post v of the armature a of the contact apparatus R.

The solenoid S' is connected to the binding-post p' and to the lower carbon-holder, K'. The binding-post p is further connected by way of the post o and the coil of the electro-magnet m to the upper-carbon holder K, all as shown clearly in the diagram Fig. 4.

The solenoids S and S' serve, together with the contact apparatus R, to properly regulate the proper distance of the carbon points from each other so as to maintain an arc of uniform size.

In order to adjust the lamp to currents of different strength, a coiled spring, f, is arranged in a casing, f', back of a gear-wheel, d', the shaft f' of which turns in suitable bearings of one of the transverse side strips, e, of the lamp-casing, as shown in Fig. 2. Both side strips are attached to vertical side strips, n, of the casing C. The gear-wheel d' meshes with a pinion, d, on the axis x, so that by regulating the tension of the spring f the strain on the axis x is increased or decreased, as required by the current with which the lamp is worked.

In order to regulate or equalize the movements of the carbon-holders so that no objectionable unsteadiness of the light shall occur, one of the carbon-holders is connected with

the piston-rod of a hydraulic brake, K², of the usual construction.

The voltaic arc is established and maintained between the carbon points in the following manner: When the carbons are in contact, the current, entering at the binding-post *p*, takes the shortest course, by way of post *o*, the coil of electro magnet *m*, the upper carbon, lower carbon, and solenoid *S'*, to the binding-post *p'*. The armature *a* is thereby instantly attracted and the lower-carbon holder *K'* drawn into its solenoid *S'*, whereby the upper-carbon holder is raised by the action of the friction-pulleys *h* *H*, and thereby the arc established between the carbon points. A branch current passes simultaneously from the binding-post *p* through the inner coil, *t'*, and the outer coil, *t*, of solenoid *S* to the binding-post *p'*, so as to neutralize thereby the action of solenoid *S* on the lower-carbon holder. The coils *t* and *t'* normally form one continuous coil, the coil *t* being short-circuited by the action of the contact apparatus or cut-out *R*. As the carbon points are consumed the resistance to the passage of the current is gradually increased, and thereby the current passing through solenoid *S'* weakened, while that passing through the outer coil, *t*, of solenoid *S* is proportionately strengthened. The upper-carbon holder is thereby drawn down by coil *t*, and the carbon points are caused to approach each other and the normal condition of the currents in the solenoid is re-established. In case for any cause the carbon points approach too closely to each other, the lower-carbon holder is attracted in a higher degree by the increased strength of the current in the solenoid *S'*, while the current in the solenoid *S* becomes weaker, which causes the separation of the carbon points. If the carbon points, however, should recede from each other to such an extent that the resistance between the points is too great to be overcome by the current, then the armature *a* of the electro-magnet is released and the current conducted from binding-post *p* over post *o*, contact-screw *b*, armature *a*, post *v*, outer coil, *t*, of solenoid *S* to the binding-post *p'*. The upper-carbon holder *K* is there-

by drawn down into the solenoid *S* and the lower-carbon holder *K'* raised by the action of the disks *H* *h*, whereby the carbon points are brought into contact, but instantly separated again, so as to re-establish the arc between the same by a branch current, which passes from the insulated post *o* through the coil of the electro-magnet *m* to the upper-carbon holder, thence to the lower-carbon holder and the solenoid *S'* to the binding-post *p'*. The armature *a* is thereby attracted again by the electro-magnet *m*, and the current that has before passed from the post *o* over set-screw *b*, armature *a*, and insulated post *v* to the exterior coil of the solenoid *S* interrupted, but the branch current from the binding-screw *p* through the inner and outer coils of the solenoid *S* and to the binding-screw *p'* re-established. By the alternating course of the current the arc is regulated and maintained in a reliable and uniform manner.

If the lamp is to be suspended, the carbons have to be arranged at the lower part of the casing, in which case the relative location of the operating parts is correspondingly changed to suit this arrangement.

Having thus described my invention, I claim as new and desire to secure by Letters Patent—

1. The combination of the carbon-holders *K* *K'*, having soft-iron extensions, solenoids *S* *S'*, inclosing the soft-iron extensions, friction contact-pulleys *H* *h*, regulating-spring *f* *f'*, gear-wheel *d'*, and pinion *d* on the axis *x* of the pulleys *H* *h*, substantially as specified.

2. The combination of the carbon-holders *K* *K'*, having soft-iron extensions, solenoid *S*, formed of an exterior coil, *t*, and an interior neutralizing-coil, *t'*, wound in opposite direction thereto, solenoid *S'*, contact apparatus *R*, and friction contact-pulleys *H* *h*, substantially as set forth.

In testimony that I claim the foregoing as my invention I have signed my name in presence of two subscribing witnesses.

CHRISTOPHER PETER JÜRGENSEN.
